Inventor;

O. E. Halin
per atty. A. H. Evans & Co

UNITED STATES PATENT OFFICE.

OLE E. HALIN, OF SAN FRANCISCO, CALIFORNIA.

DERRICK.

SPECIFICATION forming part of Letters Patent No. 314,015, dated March 17, 1885.

Application filed January 26, 1885. (No model.)

To all whom it may concern:

Be it known that I, OLE E. HALIN, of the city and county of San Francisco, and State of California, have invented an Improvement 5 in Derricks; and I hereby declare the following to be a full, clear, and exact description thereof.

My invention relates to a new and useful derrick; and it consists in a platform supported by peculiarly-hinged folding legs, horizontal, spaced, and intermeshing gears, bearing sprocket or chain pulleys between them, a chain-tackle passing around and between the chain-pulleys and over guide-pulleys in 15 the platform, a retaining-pawl for the chain, a hinged lever and ratchet-wheel mechanism between it and the driving-shaft of the operating-gears, and in a mechanism for throwing the lever out of engagement, all of which I 20 shall hereinafter fully explain.

The object of my invention is to provide a simple, powerful, and effective derrick.

Referring to the accompanying drawings, Figure 1 is a perspective view of my derrick. 25 Fig. 2 is a top view of same.

A is a platform having legs B, here shown as three in number. The upper ends of these are connected with the bottom edge of the platform by means of link-hinges C, which 30 are pivoted to both platform and legs, whereby in folding the legs may have sufficient play to prevent any straining on the hinges, and still when forced into a proper position, are adapted to form a support for the platform. The object in having the legs to fold is to render the 35 derrick readily transportable and easily set up.

On the platform is a bracket or boxing, D, in which are mounted the vertical shafts e, carrying the pairs of intermeshing spaced 40 gears E. Between the gears of each pair is a sprocket-wheel or chain-pulley, F.

G is the chain-tackle. The chain passes up through the platform and over a vertical guide-pulley, H, and between the chain-pulleys, 45 both of which engage its links. It thence passes around the back of one of them and forward again, down over a guide-pulley, H', to the block of the tackle, and thence up to the point of attachment under the platform.

I is a pawl secured to one end of the boxing

and adapted to engage the chain to prevent its moving back. This pawl is released by a cord, i, attached to it, and which hangs down within reach of the operator.

The shaft e of one of the operating-gears 55 extends upwardly beyond the boxing and is provided with a ratchet-wheel, J.

K is the operating-lever consisting of a beam or pole, made as light as may be consistent with strength. The upper end of the lever is 60 hinged to a rectangular sleeve, L, the bottom of which is provided with a ratchet-disk, l, which engages with the ratchet-wheel J when the two are brought into relation by the reason of the ratchet l fitting upon the projecting end 65 of shaft e. By rotating the lever the gears are operated to raise the chain-tackle, as is obvious.

When necessary to haul down the tackle again, it is necessary to throw the lever out of 70 engagement, or else to allow it to swing around in a reverse direction. This is not desirable, and therefore I have the forked lever M, the arms of which bear under the rim of the ratchet-disk l, and are pivoted to stops m on the 75 top of the boxing D. With this lever is connected a cord, N, by which, when pulled upon, the arms of the lever bearing on the stops m as fulcrum-points, raise the ratchet-disk l and lever K out of engagement.

Having thus described my invention, what I claim as new, and desire to secure by Letters Patent, is—

1. In a derrick, the elevated load-supporting platform A, in combination with the folding legs B, substantially as described. 85

2. In a derrick, the elevated load-supporting platform A, in combination with the legs B, and the pivoted hinge-links C, by which the legs are united to the platform, substantially as and for the purpose herein described. 90

3. In a derrick, the elevated platform A, having the intermeshing gears E and chain-pulleys F, in combination with the chain-tackle G, engaged by said pulleys and operated by the gears, substantially as herein described. 95

4. In a derrick, the elevated platform A, the horizontal, spaced, and intermeshing pairs of gears E, and the intervening chain-pulleys 100

F, in combination with the chain-tackle G, engaged by the pulleys and operated by the gears, substantially as herein described.

5. In a derrick, the elevated platform A, the horizontal, spaced, and intermeshing pairs of gears E, and the intervening chain-pulleys F, in combination with the vertical guide-pulleys H H', and the chain-tackle G, guided by the pulleys H H', engaged by the pulleys F and operated by the gears, substantially as herein described.

6. In a derrick, the elevated platform A, the horizontal, spaced, and intermeshing pairs of gears E, and intervening chain-pulleys F, in combination with the chain-tackle G, engaged by the pulleys and operated by the gears, the retaining-pawl I, engaging the chain and cord i, by which the pawl is disengaged, substantially as herein described.

20 7. In a derrick, the elevated platform A, the horizontal, spaced, and intermeshing pairs of gears E, and intervening chain-pulleys F, by which the hoisting-tackle is operated, in combination with the lever K on the shaft of one of the pairs of gears, substantially as herein described.

8. In a derrick, the elevated platform A, the horizontal, spaced, and intermeshing pairs of gears E, and intervening chain-pulleys F, 30 by which the hoisting-tackle is operated, and the ratchet-wheel J, on the shaft of one of the pairs of gears, in combination with the lever K, hinged and fitted upon the shaft, and having a ratchet-disk, l, engaging the ratchet-wheel J, substantially as herein described.

35 9. In a derrick, the elevated platform A,

the horizontal gears E, and chain-pulleys F, by which the hoisting-tackle is operated, and the ratchet-wheel J on the shaft of one of the gears, in combination with the lever K, the hinged sleeve L and the ratchet-disk l, fitted on the shaft and engaging the ratchet-wheel J, substantially as herein described.

10. In a derrick, the elevated platform A, the horizontal gears E, and chain-pulleys F, 45 by which the hoisting-tackle is operated, and the ratchet-wheel J on the shaft of one of the gears, in combination with the lever K, the hinged sleeve L and the ratchet-disk l, fitted on the shaft and engaging the ratchet-wheel, 50 and the forked lever M, bearing under the ratchet-disk and fulcrumed on stops m, and the cord N, by which the lever M is operated, substantially as and for the purpose herein described.

11. A derrick consisting of the combination of the elevated platform A, the folding legs B, the horizontal, spaced, and intermeshing pairs of gears E, and intervening chain-pulleys F, the chain-tackle G, the retaining-pawl I, the hinged ratchet-lever K, engaging a ratchet-wheel on the shaft of one of the pairs of gears, and the forked disengaging-lever M, all arranged and adapted to operate substantially as herein described.

In witness whereof I have hereunto set my hand.

OLE E. HALIN.
